UNITED STATES PATENT OFFICE

FREDERICK C. GEDGE, OF PLAINFIELD, ILLINOIS

EQUALIZING FEED MEANS FOR WATER TUBE BOILERS

Application filed October 5, 1927. Serial No. 224,077.

My invention relates to feed means for steam boilers and has particular reference to a feed pan for use with water tube boilers in which the water is fed into the feed pan and passes therefrom in the form of thin sheets of water which pass over the edges of the feed pan and come into contact with the steam. The feed water in this form is quickly heated to substantially the same temperature as the water already in the boiler, thus preventing injurious results caused by bringing cold feed water in contact with the hot boiler surface.

Another and further object of my invention is the provision of feed means in which hammering of the pipes, check valves and the like, is prevented because the pipes used for conveying the feed water into the boiler are kept sealed at all times, thereby preventing the entry of steam into these pipes which causes hammering of the check valves and water pipes and the like.

Another and further object of my invention is the provision of a feed pan in which the accumulation of mud, scale and the like, is prevented in the boiler itself, thus rendering the boiler more efficient in steam production.

Another and further object of my invention is the provision of a feed water means in which the entrained oxygen carried by the water is removed from the incoming feed water before it comes in contact with parts of the boiler subject to oxidation, this result being accomplished by feeding the water out of the feed pipe in a thin sheet which coming in contact with the steam already formed in the boiler, drives out the oxygen into the steam as the temperature of the feed water is raised.

These and other objects of my invention will be more fully and better understood by reference to the accompanying sheet of drawings, and in which—

Figure 1 is a cross sectional view of the usual water tube boiler, embodying my invention;

Figure 2 is a longitudinal sectional view of the feed water pan and water connections employed in connection with my invention;

Figure 3 is a plan view on lines 3—3 of Figure 2;

Figure 4 is a vertical sectional view on lines 4—4 of Figure 2; and

Figure 5 is a detailed sectional view on lines 5—5 of Figure 2.

Referring now specifically to the drawings, a boiler shell 10 is shown having a steam header 11 mounted therein and also having a lower water header 12. An upper header 13 is also provided, the headers 12 and 13 being connected by a plurality of tubes 14, 14 and the headers 11 and 12 being connected by a plurality of pipes 15, 15, a plurality of short pipes 16 connecting the headers 11 and 13, this combination forming what is usually termed the primary circuit in water tube boilers. A header 17 is provided which is connected with the header 12 by a plurality of tubes 18, 18 which forms what is known as the secondary circuit, it being usual to introduce the boiler feed water into the header 17.

Mounted in the header 17 and extending longitudinally thereof, is an elongated tubular feed pan 19, suitably supported in the header 17 above the usual water line in the header 17 by brackets 20, 20 and through which inverted U-bolts 21, 21 pass so that the pan 19 is held in fixed position in the header 17. In mounting the pan in the header 17 it is necessary that the feed pan 19 be level so that the water draining therefrom passes out with an equal volume throughout the entire length of the feed pan 19. In each end of the feed pan 19 are steel heads 22, 22 which are welded in position, thus effectively closing the ends of the feed pan 19. The upper side of the feed pan 19 has a plurality of elongated slots 23, 23 formed therein through which the feed water passes from the pan 19 over the sides thereof and into the header 17 in sheet-like formation, thus bringing the water into intimate contact with the steam in the header 17 and raising its temperature to substantially the same degree as that of the water in the boiler, and also driving the entrained oxygen out of the water. The slots 23 are less in width than the diameter of the feed pan, thus forcing the

water to pass over a considerable surface of the feed pan as it flows therefrom.

A pair of feed water pipes 24 and 25 are provided, the said pipes 24 and 25 being welded to the feed pan 19 and have their ends projected into the feed pan and terminating adjacent the bottom of the feed pan 19 so that there is sufficient clearance for the discharge of the feed water from the pipes 24 and 25 into the pan 19. Pipe unions 26 are provided by means of which sections of the feed pipes are connected together in the usual manner.

In operation, the feed water is fed into the boiler through the pipes 24 and 25 in the usual manner, and is discharged into the feed pan 19 and out through the slots 23 over the sides of the pan 19 and into the header 17. The feed pan 19 is filled with water at all times regardless of the rate of feed into the boiler, thus sealing the ends of the feed pipes 24 and 25 preventing steam from entering these pipes, flowing backward therethrough and causing a destructive hammering of the check valves and water pipes common in feed water systems for boilers. The feed water leaving the pipes feeding the feed pan 19, is discharged through the slots 23 which extend throughout the entire length of the feed pan in thin sheets which pass over the surface of the feed pan 19 intermediate the ends thereof on each side of the slots 23 and downward into the header 17 and into the pipes 18. The feed pan 19 being level the water is discharged along the entire length of the feed pan 19 thereby equally distributed throughout the entire series of water tubes 18 so that an unusual quantity of water or load is not thrown upon a particular section of the water pipes 18, which is common with the feeding apparatus now in use.

The feed pan can be removed from the boiler for the washing out of mud and dirt which accumulates therein but because of the even distribution of the feed water, the dirt and mud carried by the feed water is not caused to collect at one point in the boiler thus sealing up some of the tubes in the boiler and causing them to burn out. And it will also be understood that the welding of the feed water pipes to the feed pan prevents any withdrawal of these pipes away from the feed pan due to the contraction and expansion of the parts of the boiler, and insures that the ends of the feed water pipes are always submerged in water to prevent the entry into these pipes of steam from the boiler.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. Water supply means for boilers comprising in combination, a feed pan extending longitudinally of the boiler above the normal water line thereof, having slots in the upper side thereof extending substantially the entire length of the feed pan, brackets upon which said feed pan is mounted, and a feed water pipe extending into said feed water pan and terminating adjacent the bottom thereof, the said feed water pipe extending into said feed pan in a vertical direction. 70 75

2. Water supply means for boilers comprising in combination, a feed pan circular in form and closed at each of its ends and having slots in the upper side thereof extending substantially throughout its entire length, brackets secured to the header for supporting said feed pan above the normal water line of the boiler, and water supply pipes extending into said feed pan and terminating adjacent the bottom thereof. 80 85

3. Water supply means for boilers comprising in combination, a feed pan circular in form and closed at each of its ends and having slots in the upper side thereof extending substantially throughout its entire length, brackets secured to the header for supporting said feed pan in the steam space in said boiler, and water supply pipes extending into said feed pan and terminating adjacent the bottom thereof, the said slots being of less width than the diameter of the feed pan. 90 95

4. A boiler having a water distributing member extending longitudinally of a boiler drum, in the steam space thereof, said member having spillway openings for uniformly discharging the feed water throughout the length of said drum in sheet-like form, means supporting said member in the drum, and a water supply pipe whose outlet terminates at an elevation lower than said spillway openings. 100 105

5. A boiler having a water distributing member extending longitudinally of the boiler drum and having slots in the upper side thereof, the said slots being less in width than the diameter of the said water distributing member and forming spillways for uniformly discharging the feed water throughout the length of said drum, means supporting said member in said drum above the water line thereof, and a water supply pipe extending into said member and terminating below the level of the spillway openings. 110 115 120

Signed at Joliet, Illinois, this 28th day of September, 1927.

FREDERICK C. GEDGE.
